CARLOAD ADJUSTING MEANS

Enrico Prati, Asti, Calif.

Application October 7, 1946, Serial No. 701,709

9 Claims. (Cl. 105—369)

1

This invention relates to means for adjusting the load in a railroad car or the like for the purpose of providing a compact load in transit and for facilitating removal of the load at its point of destination.

In loading a railroad car with cases, boxes or other uniformly shaped units of freight, the units are stacked in layers or tiers throughout the length of the car until it is filled. The stacking is generally done by hand and even the most skilled workmen are unable to stack cases or boxes so closely that the car will be tightly packed from end to end with no space remaining for the load to shift while the car is in transit. Even a load which is comparatively tightly packed will have some space between its individual units. Some units, such for example as fibreboard cartons or cases, are sufficiently compressible to permit the entire load to move toward one end of the car in transit. This results in a space at the opposite end of the car or at some point throughout its length. In many cases, the space so formed is large enough to permit some of the units to lean or fall out of their proper place and, upon subsequent shifting of the load in the opposite direction, to be crushed or damaged. The consequent losses are particularly great where the cases contain bottled liquids because breakage of bottles causes wetting of the fibreboard cases which often makes them slump and destroys the symmetry and solidity of the entire load.

It is an object of the present invention to provide means for eliminating the losses which occur in the above described manner and particularly to provide means for adjusting a car load to compact it preparatory to transit and to loosen it for unloading. A further object of the invention is to provide means by which the contents of a fully loaded car can be adjusted from the exterior of the car. Still further and more specific objects and advantages of the invention are made apparent in the following description wherein reference is made to the accompanying drawings for a detailed disclosure of the invention.

In the drawings:

Fig. 1 is a horizontal sectional view through a refrigerator car equipped with a load adjusting means according to the present invention;

Fig. 2 is a central vertical longitudinal section through the same car;

Fig. 3 is an enlarged transverse section through a portion of the car;

2

Fig. 4 is a perspective view of a portion of the auxiliary floor shown in Figs. 1 and 2;

Fig. 5 is an enlarged fragmentary detail of a portion of the auxiliary floor;

Fig. 6 is an enlarged fragmentary sectional view taken on line VI—VI of Fig. 1;

Fig. 7 is a section on line VII—VII of Fig. 6;

Fig. 8 is an enlarged detail of a ratchet and pawl mechanism shown in Fig. 1; and

Fig. 9 is a fragmentary view illustrating a modification of a part of the invention shown in Fig. 2.

The invention is illustrated in the drawings as applied to a refrigerator car which has side walls 10, end walls 11, a bottom 12 and a top 13. Ice bunkers illustrated at 14 are formed in opposite ends of the car in a conventional manner by the provision of partitions 16 with spaces 17 and 18 adjacent their tops and bottoms to permit the free circulation of cold air between ice contained in the bunkers and the freight in the car. The invention is equally well adapted to a common box car that does not have ice bunkers at its ends and the manner in which it will be applied to such a car will be evident from an understanding of the present disclosure.

In loading a car with cartons or cases, the load is stacked beginning from opposite ends and progressing toward the center of the car where access doors 19 are provided. In order to adjust or compact the load after the car has been fully loaded, the present invention provides a pusher plate 20 adjacent one end of the car or adjacent one of the ice-bunker partitions 16 which forms the end wall of the space within the car to be loaded. This plate 20 is arranged to be advanced slowly but forcibly toward the opposite end of the car and therefore to engage and slide the load toward the opposite end of the car until all of the units of the car are compactly arranged therein. The plate 20 may engage the floor rack 26 as well as the load but the result of compacting the load will be substantially the same. In order to advance the plate 20 which is preferably of heavy sheet metal or other rigid construction, the plate has, as shown in Fig. 6, a pair of tubular members 21 secured to it and extending through the bunker 16 toward the end 11 of the car. Nuts 22 are fixed within and carried by the tubes 21 and receive threaded rods 23 journaled in bearings 24 formed in a lubricant case 25. Worm gears 26 are secured to each of the rods 23 within the lubricant case 25 and mesh with worms 27 both carried by a rod 28 which extends transversely of the car within the lubri-

cant case 25. The rod 28 has ends 29 (see Fig. 1) preferably squared for the reception of a wrench or the like and extending outwardly a short distance beyond the side walls of the car. A tube 30 (see Fig. 6) extends between the case 25 and the bunker wall 16 to protect exposed portions of the mechanism just described, and preferably a rigid angular member 33 (see Figs. 6 and 7) is disposed over each of the tubes 30 for further protection against damage by large chunks of ice as the bunker is being filled by depositing ice through doors or hatches, not shown, conventionally arranged in the roof of the car. When the car has been completely loaded from end to end with tiers of cases or boxes, the pusher plate 20 is advanced to adjust the load or to slide all of the cases or boxes to the opposite end of the car, thus taking up the small spaces which exist between the cases and so compacting the load that it is impossible for it to slide materially in a lengthwise direction when the car is in transit. This adjustment of the load is accomplished by rotating the shaft 28 which carries the worms 27 from either of its ends 29. As the worms are in mesh with the worm gears 26, the screws 23 may in this manner be rotated to advance the nuts 22 longitudinally and thus also to advance the pusher plate 20 in a longitudinal direction with relation to the car. The shaft 29 may be rotated by any suitable ratchet wrench or by an electrically powered wrench engageable with the squared ends of the shaft. Rotation of the shaft 29 in one direction will tighten or compact the load longitudinally of the car in a manner to prevent endwise shifting. Rotation of the same shaft in the opposite direction will relieve the pressure which compacts the load so that it will be loosely positioned within the car to facilitate its removal unit by unit in the conventional manner through the doorway 19.

With certain types of loads and particularly loads of light weight the construction so far described will be adequate for the purpose of preventing endwise shifting of the car. However, with car loads of heavy cased goods such as bottled liquids or canned fruit products the tremendous weight of the load itself may resist adjustment in the manner and by the means described, and furthermore when the adjusting means is retracted for unloading a load of heavy cases the load may remain so compactly arranged as to interfere with its convenient removal from the center of the car.

It is conventional practice in cars of this kind to provide auxiliary floors in the form of racks made in sections and overlying the main car floor. According to the present invention, an auxiliary floor is provided which is made up of sections or racks capable of adjustment longitudinally within the car in a manner and for a purpose to be made apparent. As shown in Figs. 1 and 2, the car of the present invention is provided with four pairs of floor racks 36, 37, 38 and 39. Each of the several floor racks is made up of timbers such as two by fours illustrated at 40 (see also Fig. 4) and in some cases plate members 41 at one edge of the rack. Tie bolts 42 extend through all of the timbers in each rack at spaced intervals and spacing members 43 are interposed between the adjacent timbers in each rack to hold them in properly spaced relation when nuts on the ends of the tie bolts are drawn tight. Each rack is provided with angular members 44 at its side adjacent the car wall and these angular members

are perforated as at 45 in Fig. 4 to receive pipes or bars 46 as illustrated in Fig. 1 which extend longitudinally of the car. The bars 46 are supported adjacent the car walls by eye bolts 47. As the bars 46 extend through the perforations 45 in the angles 44, the racks are free to slide longitudinally of the car and are also free to be swung upwardly against the car walls 10 to the broken line position shown at 48 in Fig. 3. In this position they may be secured as by hooks 49 pivoted to the walls of the car for that purpose. The position of the floor racks shown in broken lines in Fig. 3 is provided for their disposal when an auxiliary floor is not required in the car. In order that the racks when in such out of the way position will not obstruct the doorways 19, the timbers of adjacent sets of racks are staggered with relation to each other as illustrated in Fig. 1 so that the two sets of racks 36 and 37 may be advanced or telescoped in a right hand direction toward one end of the car while the racks 38 and 39 may be advanced to a telescoped position in a left hand direction toward the opposite end of the car. Because of means presently to be described, the racks 36 and 37 can not conveniently be telescoped sufficiently to clear the doorways 19 and it is therefore desirable that recesses 50, as shown in Fig. 1, be provided for their reception as they slide away from the central doorways 19. These recesses 50 are provided by offsetting the bunker wall 16, as shown.

All of the floor racks are supported on rollers for sliding movement or adjustment longitudinally of the car and these rollers, shown at 51 in Figs. 1 and 2, may be carried in recesses in the floor of the car with suitable metal strips as indicated at 53 to provide bearing support. The rolls may be made of heavy pipe or bar stock as desired. A modified form of roller is shown in Fig. 9 where rollers 54 are carried in bearings 55 secured directly to the timbers 40 of the floor rack to bear upon the surface of the floor 12. With all of the floor racks in a horizontal position as shown in Fig. 1, the car may be fully loaded with its contents resting on these racks and, when the pusher plate 20 at one end of the car is advanced toward the opposite end, the load thus supported on sets of racks capable of sliding longitudinally of the car will be more readily adjusted upon movement of the plate 20 and will move toward the opposite end of the car in four separate sections. This overcomes the greater part of the friction that would be encountered if the plate 20 were advanced to move a full car load that was not so supported.

In addition to the means just described for advancing the load toward one end of the car, retraction of the plate 20 to loosen the load when the car is to be unloaded effects retraction of one-half of the load, or that portion of the load supported on the floor racks 36 and 37, away from the center of the car without moving the other half of the load. The load is thus split or opened centrally to facilitate removal of its units through the doorways 19. This is accomplished by hooks 60 shown in Figs. 1 and 2 which are pivotally supported adjacent the lower edge of the plate 20 and which ride on the bottom of the car in notches which have upwardly inclined portions 61. When the plate 20 is advanced to the left as viewed in Fig. 2 the hooks 60 will ride up the incline 61 until their hooked ends are in position for engagement with the tie bars 42 at the right ends of the racks 36. Thus, upon retraction of the plate 20 the racks 36 are engaged

and retracted with it. The racks 36 are also connected with the racks 37. Each rack 36 has one long timber 40a provided with a notch 62 which, as shown in Fig. 5, embraces the tie bar 42 in the corresponding adjacent rack 37. This notch is elongated to permit relative telescoping movement of the racks 36 and 37 toward each other but when the rack 36 is withdrawn or moved to the right as viewed in Figs. 1 and 2, the end of the notch engages the spacer 43 which surrounds the tie bar 42 of the rack 37 and the racks 37 are in this manner also retracted away from the center of the car when the plate 39 is retracted. When the load has been placed in the car and the plate 29 advanced to compact it, it is preferable to hold at least one of the rack supporting rollers 51 against rotation and this may be accomplished by a ratchet 65 as shown in Figs. 1 and 8 secured to a squared end of the roller 51 and having a pivoted pawl 66 engageable therewith to prevent rotation of the roller in a load loosening direction. The ratchet 65 is shown as disposed outside the car and carried at the end 51 of a roller that has been extended through the wall of the car. The pawl 66 is likewise pivoted to the exterior of the car wall. Similar ratchet and pawl mechanisms may if desired be employed at either end of the shaft 29 to prevent its rotation after the car load has been compacted though this may not in all cases be necessary because the pitch of the worm gears 26 may be such as to prevent them from operating in a reverse direction except when the shaft 28 is rotated.

I claim:

1. In a freight car or the like, an auxiliary floor comprising floor racks formed in sections moveable with relation to each other longitudinally of the car, whereby a load of freight supported on said racks may be adjusted lengthwise of the car by pressure exerted from one end of the load.

2. In a freight car or the like, an auxiliary floor comprising floor racks formed in sections moveable with relation to each other longitudinally of the car, whereby a load of freight supported on said racks may be adjusted lengthwise of the car by pressure exerted from one end of the load and anti-friction means between the racks and the car floor.

3. In a freight car or the like, an auxiliary floor comprising a plurality of floor racks adapted to support freight and adjustable longitudinally of the car with relation to each other, and means adjacent an end of the car adapted to be advanced toward its opposite end for adjusting the compactness of freight supported on said racks.

4. In a freight car or the like which has an opening centrally of its length for loading and unloading freight, floor racks for supporting freight in the car and adjustable longitudinally thereof, means within the car adjacent one end for compressing a load of freight supported on said racks, means for retracting said compressing means, and means operable upon such retraction for adjusting the floor racks on one side only of said central opening to facilitate unloading of the freight.

5. In a freight car or the like with a central access opening, freight supporting racks overlying the car floor, rollers supporting the racks for adjustment lengthwise of the car, a load compressing means operable from one end of the car to move the freight and racks by which it is supported in sections toward the opposite end of the car, means for retracting the load compressing means, and means operable upon retraction thereof to engage the racks between the said one end of the car and the center to facilitate unloading of the car from the central access opening.
10. In a freight car or the like the combination of a load engaging and compressing means disposed at one end of the car, and a plurality of load supporting floor racks, disposed for sliding movement on the car floor to permit compression of the load in sections smaller than the full car load.
15. In a freight car or the like the combination of a load compressing means arranged to compact the load by pressure upon one end thereof and means for supporting the load in separate sections independently movable lengthwise of the car.
20. Means for compacting a load in a cargo space to prevent shifting of the load in transit which comprises a plurality of load supporting members, means supporting said members for movement parallel to and relative to the floor of the cargo space and relative to each other, and load compressing means adjacent one side of said space to compress the load toward an opposite side thereof and in the direction of movement of said load supporting members.
25. Means for compacting a load in a cargo space to prevent shifting of the load in transit which comprises a plurality of load supporting members, means supporting said members for movement parallel to and relative to the floor of the cargo space and relative to each other, and load compressing means adjacent one side of said space to compress the load toward an opposite side thereof and in the direction of movement of said load supporting members, said load supporting means including anti-friction means interposed in supporting relationship between the load supporting members and the floor
30. of the cargo space.
35. In a freight car or the like, an auxiliary floor comprising floor racks formed in sections moveable with relation to each other longitudinally of the car, whereby a load of freight supported on said racks may be adjusted lengthwise of the car by pressure exerted from one end of the load.
40. In a freight car or the like, an auxiliary floor comprising floor racks formed in sections moveable with relation to each other longitudinally of the car, whereby a load of freight supported on said racks may be adjusted lengthwise of the car by pressure exerted from one end of the load.
45. In a freight car or the like, an auxiliary floor comprising floor racks formed in sections moveable with relation to each other longitudinally of the car, whereby a load of freight supported on said racks may be adjusted lengthwise of the car by pressure exerted from one end of the load.
50. In a freight car or the like, an auxiliary floor comprising floor racks formed in sections moveable with relation to each other longitudinally of the car, whereby a load of freight supported on said racks may be adjusted lengthwise of the car by pressure exerted from one end of the load.
